STRANDED RIBBON HANGER

James E. Talbott, Dobbs Ferry, N. Y., assignor to
 Anaconda Wire & Cable Company, New York,
 N. Y., a corporation of Delaware

Application December 19, 1934, Serial No. 758,199

4 Claims. (Cl. 248—61)

This invention relates to improvements in hangers of stranded metallic wire of flat ribbon-like construction.

For many years, it has been the common practice to suspend insulated electric cables from an overhead support in the nature of a high tensile strength stranded cable, usually called a "messenger wire". The messenger wire provides the tensile strength lacking in the insulated electric cables, the latter usually being made of copper, aluminum and the like, while the messenger wires are frequently made of steel. At spaced intervals, cable hangers are arranged along the messenger wire to suspend the insulated electric cable.

The earlier types of cable hangers were usually made of galvanized steel or copper weld wire of sufficient strength, which was hooked over the messenger cable and encircled about the insulated cable. While in some cases such prior wire hangers function satisfactorily from a tensile strength standpoint, they are open to the serious objection that they cut into the sheath of the insulated cable, seriously injuring the same and ultimately causing the failure of the sheath and the cable itself.

Attempts have been made to overcome this objectionable feature by the provision of hangers formed of marline, which encircles the insulated cable and the messenger and is secured by a special type of tied knot. In other attempts to overcome the objectionable feature of the hanger wires cutting into the cable, textile fabric hangers have been used having fittings or buckles and the like for securing the same to the messenger. The marline and the textile fabric hangers are open to the serious objection that they are subject to early destruction due to exposure to the elements, it being obvious that they must withstand snow, rain and excessive temperature changes between seasons. This quickly rots the organic materials of the textile fabric hangers and results in an excessive maintenance cost, which of course is objectionable from an economic standpoint.

To overcome the shortcomings of the prior practice above referred to, such as the excessive abrasion and cutting of the wires on the one hand and the rotting or disintegration of the organic marline or fabric on the other hand, I have devised an improved cable hanger involving the use of a ribbon-like metallic braid or fabric, which provides sufficient bearing or contact area on the cable, to avoid cutting of the sheath and which is also proof against rotting to which or-

ganic materials are subjected. Preferably, the ribbon-like hanger is composed of a multiplicity of strands of metallic wire of material well suited to resist the corrosive action of the elements, such preferable material for the wire strands being a 5 cuprous metal such as copper, bronze or other alloy rich in copper.

I am not, however, limited to such cuprous metal except where the same is specifically referred to in the claims, it being apparent that 10 iron and steel either galvanized or ungalvanized may be used in some instances. The stranded body of the hanger may be either woven or braided, so long as it is substantially flat or generally 15 of a ribbon-like nature as distinguished from a round wire-like element. To the ends of the hanger ribbons of my invention are secured suitable attaching devices such as hooks or other fastenings. These latter may be secured by swaging, drawing, welding or otherwise making 20 a substantially permanent union between the fastening and the hanger ribbon.

Several embodiments of the invention are illustrated in the accompanying drawing, in which—

Fig. 1 is a cross section showing a typical installation of overhead conductor supported from a messenger wire by my improved type of hanger; Fig. 2 is a side view of Fig. 1; Fig. 3 is a perspective view of one type of hanger embodying 30 the invention; Fig. 4 is an enlarged detail of one end of the hanger; Figs. 5 and 6 are details of modified forms of attaching devices; Fig. 7 is a plan view of a further modification of attaching device.

Referring in detail to the drawing, 10 represents a conventional form of overhead messenger wire which is adapted to support the insulated conductor 12 by means of my improved ribbon-like hanger indicated at 14. This hanger, as 40 shown in Fig. 2, has an intermediate portion wrapped about the cable and it carries attachment fittings 16. These fittings, as illustrated in Figs. 1 to 4 inclusive, are of hook-like form. They may be readily produced from stock size 45 tubing somewhat flattened out by a pressing operation, the ends of the hanger ribbons being inserted in the tubing and then subjected to a swaging operation. Alternatively, the tubing from which the fittings are formed may be subjected to a drawing operation so as to cause an intimate engagement with the strands of the ribbon-like hanger. The swaging or drawing operation, it will be understood will cause the metal to flow between the interstices of the strands and 50 55

thus effect a secure mechanical engagement between the joined parts. Alternatively, if desired, the ribbon 14 may be secured by a rivet 18, as illustrated in Fig. 7. And instead of employing a fitting of hook-like form, I may provide terminals of the character shown in Figs. 5 and 6, wherein one attachment fitting is provided with a keyhole aperture 20 adapted to be interlocked with the headed stud 22 on the attachment fitting 5 of Fig. 6. It is also contemplated that the hanger ribbon may be secured in place by an attachment resembling a belt buckle with a tongue to fit into corresponding holes in the ribbon, or I may employ a fastener similar to the type of belt buckle wherein a clamping action is obtained.

From the foregoing, it will be apparent that my invention provides an improved hanger in the nature of a flat ribbon composed of a multiplicity of braided or interwoven strands which 10 will give a maximum strength with a minimum weight and which cannot be readily destroyed by the elements and which would not have the objectionable feature of cutting into the cable or its insulation.

25 The hanger of my invention, while peculiarly well suited for supporting cables from an overhead messenger wire, is also suited for sustaining cables from other overhead supports and it is also adapted for supporting pipes, or other 30 elements requiring suspension. The non-cutting characteristics of the hanger are particularly well suited for the hanging of heater pipes wrapped with asbestos or other insulation.

While I have described quite specifically the

embodiments of the invention herein illustrated it is to be understood that the disclosure is to be interpreted in an illustrative rather than a limiting sense and the claims are to be construed as broadly as is consistent with the teachings of the prior art.

What I claim is:

1. A hanger of the character described comprising a flexible flat ribbon of braided metallic strands having two flattened tubular hooks secured thereto, one of which embraces one extremity of the ribbon and forms one terminal of the hanger and the other of which embraces the other end of the ribbon and forms the opposite terminal of the hanger. 10

2. A hanger of the character described comprising a flat ribbon of braided non-corrodible metallic strands with flattened seamless tubular terminal hooks embracing the opposite ends of the ribbon. 20

3. A hanger of the character described comprising a flat ribbon of copper strands, a respective seamless tubular attachment terminal fitting secured to each extremity of said ribbon, the two fittings adapted to cooperate in the suspension of a cable from an overhead support. 25

4. A hanger of the character described comprising a flat ribbon of braided, non-corrodible metallic strands, flattened seamless tubular hooks embracing the respective ends of said ribbon, both of said hooks being adapted to independently engage an overhead wire so as to support a cable in the bight of said ribbon. 30
